UNITED STATES PATENT OFFICE.

GERMAINE MOERLOOSE, OF NEW YORK, N. Y., ASSIGNOR TO JOSEPH STRUELENS, OF NEW YORK, N. Y.

WATER HEATER.

Application filed January 21, 1922. Serial No. 530,928.

To all whom it may concern:

Be it known that I, GERMAINE MOERLOOSE, a citizen of Belgium, and a resident of the city of New York, borough of Manhattan, in the county and State of New York, have invented a new and Improved Water Heater, of which the following is a full, clear, and exact description.

This invention relates to a water heater, 10 and has for an object the provision of an automatic water heater which is extremely simple in its operation and construction whereby the cost of manufacture and repair is reduced to a minimum.

Another object resides in the provision 15 of means whereby the heating fluid is cut off automatically whenever the flame, especially the pilot flame, goes out.

A further object resides in the provision 20 of thermostatic means responsive to changes in temperature to actuate magnetic means to close the gas valve under predetermined conditions.

A still further object resides in the particular construction and arrangement of 25 parts which are hereinafter described and claimed and shown in the accompanying drawings.

The invention is illustrated in the drawings, in which—

Figure 1 is a vertical section through the heater.

Fig. 2 is a vertical section through the casing containing the water and fuel valve, 35 taken on the line 2—2 of Fig. 1.

Fig. 3 is a horizontal section taken on the line 3—3 of Fig. 2.

The form of the invention shown in the drawings is a preferred form, although it 40 is understood that modifications in the construction and arrangement of the parts and in the character of the materials used may be adopted without departing from the spirit of the invention.

The apparatus comprises a casing 1 of any 45 suitable material within which is disposed a series of coils or pipes 2, preferably copper pipe, and preferably disposed on the form of a hollow tapered cone. These coils or pipes have connected thereto an outlet pipe 3 and an inlet pipe 4. This spiral tapered coil of piping is surrounded by a 50 conical tapered sheath of any suitable metal and also has a plurality of beveled plates 55 such as 6 and 7 supported horizontally

throughout its height within the coil to spread the heat toward the pipes and away from the center of the coil. The casing 1 has an outlet draft pipe 8, and the water coils 2 are supported on suitable brackets 60 9 attached to the inner face of the casing 1. Supported beneath the coils on suitable brackets 10 is a heater pipe 11, which is preferably supplied with gaseous fuel and automatically lighted by a pilot burner 12 65 of any suitable construction. The heater pipe 11 is connected by a pipe 13 with a cylindrical casing 14. A pilot burner 12 is connected by a pipe 15 with an elbow 16 leading to a gas chamber supplied with, preferably, 70 gaseous fuel through a gas pipe 17. To the pipe 15 adjacent the pilot burner 12 is disposed a thermostatic device 18 which is preferably in the form of a bimetallic strip. This device, when it has become deflected, 75 moves downwardly to engage with an adjustable contact 20 on a bracket 19 insulatingly supported from any suitable point. A lever arm 21 pivoted at 22 can be operated by a handle 23 disposed outside the casing 80 1 to lift the thermostatic arm 18 off the contact 20 and direct the circuit when desired and for the purpose hereinafter set forth. The bracket 19 is connected by a wire 24 with a suitable circuit. The thermostatic 85 element 18 is connected by a wire 25 to the same circuit in the manner hereinafter set forth. When the arm 21 is moved by the handle 23 to lift the thermostat arm 18, the frictional engagement between the two 90 with the arm 21 in a vertical position will hold the arm 21 in this position. As long, therefore, as the thermostat arm is cold, which occurs when the pilot light is out, the arm 18 will be held upward. Whenever 95 the pilot light, however, is lit, the thermostatic arm will be affected so that it will automatically move upward. By moving upward it will become disengaged from the lever 21, whereupon the weight of the handle 100 23 will cause the lever 21 to drop, thus moving out of the path of the thermostatic arm 18 when this arm again becomes cold. By reason of this operation it will be seen that when the handle 23 has once been operated 105 and the valve 38 lifted off its seat by means of the ring 46, as hereinafter described, the valve will be held upward.

The cylindrical casing 14, which is in reality a valve casing, contains a water-op- 110

erated valve 26 normally disposed on a seat 27 and provided with a stem 28. A water inlet pipe 29 leads to a chamber beneath the valve seat 27. The stem 28 extends through 5 a packing gland into an open chamber within the valve casing 14 and is provided with a spring 31 disposed between the packing gland and a collar 32 fixed on the stem 28. This spring tends to hold the valve 26 normally 10 on its seat 27. The valve 26 is preferably made of brass and the seat 27 is also made of brass, so that no packing between the valve and its seat is required.

A partition 33 disposed across the lower 15 portion of the cylindrical casing 14 separates the intermediate chamber from a lower gas chamber. The stem 28 extends through a packing gland 34 into this gas chamber and has on its lower end a valve 35 adapted normally 20 to be seated on a seat 36 when the valve 26 is disposed on its seat. The gas chamber beneath the partition 33 is supplied with gas through the pipe 17. This pipe 17 leads to an elbow to which is connected 25 a gas supply pipe 39. Within this elbow is disposed a seat 37 for a valve 38 which, when it is disposed on the seat cuts off the supply of gas to the apparatus. This valve has a stem 40 extending upwardly through 30 a packing gland 41 into a chamber 42 formed in the casing. This stem 40 has attached thereto a collar 43 between which and the upper end of a cover plate 50 a spring 44 extends to normally force the 35 valve 38 down on its seat. The upper end of the stem 40 is provided with a head 45, preferably formed in the shape of a truncated cone with the theoretical apex pointing downward. This head is also supplied 40 with a finger ring 46 and is normally disposed between two spring plates 47 and 48 connected at one end to a box 49. This box 49 is supported from the cover plate 50 which extends over the top of the casing 42 45 and contains a magnet 51. This magnet is adapted to actuate a latch lever 52 containing a latching finger 53 to be disposed underneath the lower edge of the head 45. The lever 52 is pivoted at 54 and is held 50 normally outward by reason of the spring 55 connected to its lower end. The battery 56 is in series with the magnet 51, with the bracket 19, the thermostatic element 18 and the wire 25. The wire 25 is connected to 55 the plate 48, and this plate is normally in circuit with the plate 47 through the head 45, the plate 47 being connected to the other side of the magnet 51 by a wire 57.

From a consideration of Fig. 3, which 60 represents this circuit, it will be seen that whenever the thermostatic element 18 closes the contact with the bracket 19 the magnet is energized, causing the retraction of the lever 52. This releases the head 45, permitting the spring 44 to force the valve 38

down on its seat. When the valve 38 is thus disposed on its seat the gas is shut off. This action of the valve takes place whenever the thermostatic element contacts with the adjustable screw 20 on the bracket 19. 70 This contact is made whenever the heat of the pilot burner drops below a certain value, especially when the pilot burner goes out. In this way an absolutely accurate means is provided which will cause the gas to be shut off as soon as the pilot burner goes out, and thus the danger of gas escaping without being burned is positively void.

The apparatus, it will be seen, is simple 80 in its construction and operation and consequently requires very little attention, needs very little repairing, and could be economically manufactured. The construction of the water coils is such that heat is most efficiently disposed along the coils coming intimately into contact therewith. The gas is turned on automatically as soon as the water commences to flow but is very quickly shut off the instant the water ceases to flow, so that no more than the necessary amount 90 of water is heated at any one time.

What I claim is:

1. A water heater which comprises a pilot light, a thermostatic element associated therewith and movable in accordance with the variations in the condition of the pilot light, an electrical contact adapted to be engaged by the thermostatic element in one position thereof, and manually operable means for positively holding the thermostatic element 100 off the contact.

2. A water heater which comprises a pilot light, a thermostatic element associated therewith and movable in accordance with the variations in the condition of the pilot light, an electrical contact adapted to be engaged by the thermostatic element in one position thereof, and a manually operable lever to engage the thermostatic element and hold it away from the electrical contact.

3. A water heater which comprises a pilot light, a thermostatic element associated therewith and movable in accordance with the variations in the condition of the pilot light, an electrical contact adapted to be engaged by the thermostatic element in one position thereof, and a manually operable lever to engage the thermostatic element and hold it away from the electrical contact, the weight of the manually operated lever being distributed so that after it has been moved to a position to engage the thermostatic element and is released by the movement of the element therefrom, the lever arm will move back to normal position by the action of 120 gravity.

4. A water heating device which includes a pilot light, a thermostat disposed in the vicinity of the pilot light and influenced by the heat from said light, an adjustable con- 130

tact associated with said thermostat, a battery in circuit with said contact, a magnet in series with said battery, a conductive plate connected to the other side of said magnet, a second conductive plate connected to the thermostatic element, a movable valve stem, a head on said valve stem adapted to bridge the space between said plate when the valve is in an elevated position, whereby the circuit is closed between said plates, the action 30 of the thermostat adapted to completely close the circuit through the adjustable contact in accordance with the movement of the thermostat under the influence of the heat or lack of heat from the pilot light.

5. A water heating device which includes a pilot light, a thermostat disposed in the vicinity of the pilot light and influenced by 20 the heat from said light, an adjustable contact associated with said thermostat, a battery in circuit with said contact, a magnet

in series with said battery, a conductive plate connected to the other side of said magnet, a second conductive plate connected to the 25 thermostatic element, a movable valve stem, a head on said valve stem adapted to bridge the space between said plate when the valve is in an elevated position, whereby the circuit is closed between said plates, the action 30 of the thermostat adapted to completely close the circuit through the adjustable contact in accordance with the movement of the thermostat under the influence of the heat or lack of heat from the pilot light, 35 latching means adapted to engage the head of the valve stem and hold it in its elevated position, said latching means adapted to be moved by the energization of the magnet to release the head of the valve stem, and 40 means for moving the valve stem downward to seat the valve when the head is released.

GERMAINE MOERLOOSE.
